ELECTRICALLY OPERATED SIREN

Lester H. Miles, Los Angeles, Calif.

Application November 14, 1927, Serial No. 233,094

3 Claims. (Cl. 171—323)

This invention relates to electrically operated sirens.

The general object of this invention is to provide an improved motor driven siren wherein the motor brushes may be retracted from engagement with the armature.

Another object of this invention is to provide an improved motor wherein the brushes are normally out of engagement with the armature and wherein means is provided for causing the brushes to engage the armature when current is directed to the motor.

A further object of the invention is to provide a motor of the class described for driving the rotor of a siren so that when the current is cut off from the motor the siren rotor and motor armature may rotate freely without the friction of the brushes on the armature.

Other objects of this invention will be apparent from the following description taken in connection with the accompanying drawings wherein:

Fig. 1 is a side elevation of my improved motor driven siren.

Fig. 2 is a central vertical longitudinal section through the siren shown in Fig. 1 and a portion of the motor.

Fig. 3 is a section taken on line 3—3 of Fig. 1 with the siren rotor removed, showing the bolts which secure the motor to the siren.

Fig. 4 is a central vertical section of one of the motor brush actuating members showing the brush in a normal or retracted position.

Fig. 5 is a diagrammatic view of the electrical hook up of the motor shown in Figs. 1 to 4 inclusive.

Fig. 6 is a central vertical longitudinal section through a siren and a portion of a motor showing a modified form of brush actuating means.

Fig. 7 is a section taken on line 7—7 of Fig. 6 showing the modified form of brush actuating means, and

Fig. 8 is a diagrammatic view of the electrical hook up of the motor and brush actuating means shown in Figs. 6 and 7.

In Figs. 1 to 5 inclusive I have shown my invention as embodied in a motor driven siren indicated generally at 10. The motor which is shown as secured to and adapted to actuate the siren is indicated generally at 11. The siren includes a casing 12, having a rotor 14 mounted therein. The motor 10 may be of usual construction except for the brushes and includes an armature 15 and an armature shaft 16 having a reduced end portion 17 on which the siren rotor 14 may be secured by any suitable means. The

shaft 16 is preferably supported in a bearing 18 in the siren casing 12 in addition to being supported in a bearing 19 on the motor but if desired the bearing 18 may be omitted.

In Figs. 1 to 5 inclusive I have shown the motor 10 as provided with two brush actuating means indicated generally at 20 but it will be understood that as many of these devices 20 may be employed in a motor as may be desired.

The devices 20 as shown each comprise a housing 22 positioned in a recess 23 in the motor case and removably secured to the motor case by any suitable means such as by cap screws 24. The housing 22 is provided with a removable cap 25 having an aperture 26 therethrough and having mounted thereon a solenoid winding 27.

Mounted within the housing 22 I provide a brush retainer 28 made of an insulating material and provided with a removable cap 29 which is likewise made of an insulating material and includes a projection 30 which is positioned in the aperture 26 of the cap 25 and has a solenoid core 31 secured thereto in any suitable manner.

A coiled spring 32 surrounds the brush retainer 28 and bears against the bottom of the housing 22 and the under side of the projecting edges of the cap 29 and normally urges the cap 29 against the bottom of the housing cap 25 as shown in Fig. 4.

The bottom of the brush retainer 28 is provided with an aperture 33 in which is mounted a brush 34 having a head 35 thereon which is of a greater circumference than the circumference of the aperture 33. A coiled spring 36 normally urges the head 35 of the brush 34 into contact with the bottom of the brush retainer as shown in Fig. 4. Any suitable means for conducting electricity to the brush 34 may be used but in the accompanying drawings I have shown a wire 38 secured to the brush and passing out through an aperture 39 in the cap 29 and the solenoid core 31.

As shown in Fig. 5 the wire 38 connects to a feed wire 39 which is connected to one pole of a battery 40 or any other suitable source of supply. The feed wire line 39 includes a control switch indicated at 41. From the opposite pole of the battery 40 a wire 42 is connected to the field of the motor which is indicated at 43.

One end of the solenoid winding 27 is connected by means of a wire 44 to the feed wire 39 through a condenser 45 and the other end of the solenoid winding is connected by means of a wire 46 to the wire 42 through a condenser 47, thus it will be seen that when the control switch 41 is closed

as shown in Fig. 5 the current will flow from the battery 40 through the feed wire 39, through the condenser 45 to the solenoid winding 27 and thence through the wire 46, through the condenser 47 to the wire 42 and back to the battery 40. As the solenoid windings 27 are energized the core 31 is pulled from the position shown in Fig. 4 to the position shown in Fig. 2, thus forcing the brush retainer 28 towards the armature 15 and allowing the brush 34 to contact with the armature.

When the brush 34 contacts with the armature 15 the current from the battery will pass through the feed wire 39 and wire 38 to the brush and thence to the armature 15 whereupon the motor 10 will operate to rotate the siren rotor 14. When the switch 41 is opened the solenoid windings 27 cease to be energized and the spring 32 forces the brush retainer to a retracted position as shown in Fig. 4, thus disengaging the brush 34 from the armature 14 whereupon the flow of current to the motor will be cut off.

In Figs. 6, 7 and 8 I have indicated a motor at 50 which includes a modified form of brush actuating means. The motor 50 is shown as secured to and adapted to operate the siren indicated generally at 51 and which includes a casing 52 and a rotor 53 mounted therein. The various elements of the motor 50 may be of usual construction except for the brushes and includes an armature 54 and an armature shaft 55 on which the siren rotor 53 is secured in any suitable manner. The armature shaft 55 is preferably supported in a bearing 56 in the siren casing in addition to being supported in a bearing 57 on the motor, but if desired the bearing 56 may be omitted.

Motor brushes 58 in this modified form are shown as mounted in housings 59 which are positioned in apertures 60 in the motor housing. Each of the brushes 58 includes an enlarged head 61 which is positioned within the housing 59 and prevents the brush from being displaced from the housing. Each of the housings 59 is provided with a detachable cap 62 and within the housings I provide a coiled spring 63 which bears against the cap 62 and the head 61 of the brush and tends to urge the brush head against the bottom of the housing.

For actuating the brushes 58 I provide a pair 50 of rings 65 and 66 which are rotatable in grooves 67 and 68 in the motor casing. The rings 65 and 66 are of like construction and are each split as at 69 to facilitate assembly. The rings 65 and 66 are preferably connected by cross bars 70 and are each provided with ears 71 in which there is provided an angular slot 72. Pins 73 extending from the brush housing 59 are positioned in the slots 72 of each ring. The ring 65 is provided with an arm 74 to which a coiled spring 75 is attached which normally tends to hold the arm 74 against the stop 76 so that the rings will force the pins 73 of the brush housings to the end of the slots 72 farthest from the center of the armature thus raising the brushes out of contact 60 with the armature.

For moving the ring 65 in the opposite direction to move the brush housing pins 73 in the slots 72 towards the armature I provide a solenoid 77 including windings 78 and a core 79. The core 79 is pivotally secured to a link 80 as at 81 and the link 80 is pivotally and slidably connected to an arm 82 of the ring 65 as at 83.

For moving the ring 65 in the opposite direction to move the brush housing pins 73 in the slots 72 towards the armature I provide a sole-

noid 77 including windings 78 and a core 79. The core 79 is pivotally secured to a link 80 as at 81 and the link 80 is pivotally and slidably connected to an arm 82 of the ring 65 as at 83.

For energizing the solenoid windings as shown in Fig. 8 a wire 85 connects one end of the windings 78 through a condenser 86 to a feed wire 87 which includes a control switch 88 and is connected to one side of a battery 89. The other end of the solenoid windings is connected by a wire 90 through a condenser 91 to another feed wire 92 which is connected to the other side of the battery 89.

The feed wire 87 connects to the field of the motor 50 and the other feed wire 92 is connected to the brushes 58 by wires 93. Thus it will be seen that when the control switch 88 is closed the current will flow from the battery 89 through the feed wire 87, through the condenser 86 to the solenoid windings 78 and thence through the wire 90, through the condenser 91 to the wire 92 and back to the battery 89. As the solenoid windings 78 are energized the core 79 will be moved and cause the rings 65 and 66 to move against the action of the spring 75 to cause the brushes to move into contact with the armature 54. When the brushes contact with the armature the current from the battery will pass through the feed wire 92 and wires 93 to the brushes and thence to the armature 54 whereupon the motor 50 will operate to rotate the siren rotor 53.

When the control switch 88 is opened the solenoid windings 78 cease to be energized and the spring 75 then moves the rings 65 and 66 to cause the brushes 58 to move out of contact with the armature 54 whereupon the flow of current to the motor will be cut off.

In using my sirens by moving the brushes out of contact with the armature, the friction of the brushes against the armature is removed and the motor rotor and the siren rotor continue to rotate at an operating speed for a considerable time after the supply of current to the motor has been cut off. This effects a large saving in electric current which is an item of considerable importance when operating the siren from the battery of a motor vehicle. The motor rotor acts as a fly wheel to maintain the momentum of the siren rotor when the current to the motor is discontinued so that the siren rotor "coasts" at an operating speed for a long time after the current to the motor is cut off.

From the foregoing description it will be apparent that I have provided a novel motor driven siren which is compact, durable and efficient in use.

Having thus described my invention, I claim:

1. In apparatus of the class described, an electric motor having an armature shaft and a commutator, a housing enclosing the commutator including an end wall rotatably receiving said shaft, brushes supported within the housing for movement to and from engagement with the commutator, a brush operating device rotatably mounted within the housing coaxially of the shaft between said wall and the commutator and including parts adapted when said device is rotated in one direction to lift the brushes from engagement with the commutator, said device when rotated in an opposite direction serving to release the brushes for return to engagement with the commutator and means for rotating said device in opposite directions.

2. In apparatus of the class described, an electric motor having an armature shaft and a commutator, a housing enclosing the commutator including an end wall having a bearing thereon rotatably receiving said shaft, brushes supported within the housing for movement to and from engagement with the commutator, a brush operating device rotatable within the housing upon the exterior of said bearing and adapted 5 when rotated in one direction to lift the brushes from engagement with the commutator, said device when rotated in an opposite direction serving to release the brushes for engagement with the commutator, means within the housing for 10 rotating said device in one direction, and separate means for rotating it in an opposite direction. 15

3. In apparatus of the class described, an

electric motor having an armature shaft and a commutator, a housing enclosing the commutator including an end wall adjacent one end of the commutator, brushes supported within the housing for movement to and from engagement with the commutator, a brush operating means 5 rotatably mounted within the housing coaxially of the shaft between said end wall and the commutator and including parts adapted when said device is rotated in one direction to move the brushes from engagement with the commutator, said device when rotated in an opposite direction releasing the brushes for return to engagement with the commutator, and means for rotating said device in opposite directions. 10 15

LESTER H. MILES.
